FOOT MEASURING DEVICE

Elmer Jared Bliss, Chilmark, Mass.

Application February 18, 1942, Serial No. 431,417

9 Claims. (Cl. 33—3)

This invention relates to foot measuring devices adapted for mailing, by the use of which customers may, with facility and accuracy, determine the size of shoes required for a proper fitting of their feet so as to enable them to order by mail and thus obviate the necessity for the customary fitting calling for their presence in a shoe store.

The measuring of feet preliminary to a trial fitting of shoes is usually accomplished while the customer is seated. The shoes selected by the aid of the measurements obtained, are then placed on the feet and the customer is asked to stand in the shoes in order to enable the clerk to ascertain by the customer's reaction to the "feel" of the shoes and his own observations whether the shoes are of the correct size, and where the fit appears to be improper to indicate, generally, the required size. More often than not several trial fittings are needed. This is primarily because the measurements taken when the feet are at rest do not truly represent the size of the feet of the customer when standing due to the distortion of the bone structure as well as of the muscle and tissue thereof in response to the weight of the body.

Any device intended for use by the customer for determining the correct size of the shoe without the benefit of trial fittings or the advantage of a clerk's experience and counsel must duplicate as nearly as possible all conditions incidental to the support of the feet and to which the feet will be subjected when encased in a properly fitted shoe with the customer standing. An important factor to be considered therefore, is that when standing normally most of the weight of a person will and should be carried by the balls of his feet.

It is an object of the present invention to provide a support for each foot of a customer, shaped to simulate the contour of the interior supporting surface of a shoe and particularly with the heel portion elevated with respect to the part intended for the support of the ball of the foot.

More specifically an object hereof is the provision of a pair of platforms of the character generally indicated above, having delineated thereon the exact location for the feet while taking their measurements, in combination with a plurality of measuring units of different sizes adapted for insertion between each foot and abutments formed at either side and in front of each foot for indicating the size of shoe needed for a proper fitting, each foot being thus measured simultaneously so as to ascertain any variation

in size between the two, and under actual conditions present in shoes worn by the customer.

Another object is to provide a composite support comprising a pair of cartons formed to receive and support, respectively, the right and left feet of a prospective customer, and hinged together along longitudinal edges thereof to permit folding of the support so as to enclose auxiliary pieces of the apparatus to facilitate mailing.

Another object is to provide the platforms by which the customer is supported when taking the measurements, with depressions, having substantially vertical walls and of a size to accommodate the largest feet capable of being fitted by the shoe distributor from whom the prospective customer wishes to buy, for retaining a plurality of blocks of multiples of one sixth of an inch in thickness, to be interposed in front of each foot and a series of strips preferably one twelfth of an inch in thickness which in use are interposed at the sides of the feet, for indicating by the number and size of the blocks and strips required to fill the area between the foot and the walls of the depression, the length and width of the shoes needed for proper fitting of the feet.

Another object is to provide retainers to delineate the proper location of the heels of the customer in positioning his feet on the platforms for measurement, said retainers being removable for storage with the measuring blocks in the depressions formed for the feet in the respective platforms when the device is prepared for mailing.

Other objects and corresponding advantages of my invention such for example as, maximum economy of manufacture, substantial duplication in the platforms of the shape of the shoe insofar as such shape affects the contour of the feet when supporting the weight of the body, and extreme simplicity of construction and use which is conducive to accurate results by the most inexperienced persons, will be apparent to those of skill in the art upon an examination of the following description and the accompanying drawing.

In the drawing:

Fig. 1 is a perspective view of a device embodying my invention as it appears when folded for mailing;

Fig. 2 is a perspective view of the apparatus with the heel retainers installed, and with the measuring blocks assembled in their relative positions as when in use;

Fig. 3 is a plan view of the apparatus as shown in Fig. 2 but with a right foot, represented by

dotted lines, in position for taking its measurements.

Fig. 4 is a perspective view taken on lines 4—4 of Fig. 3 illustrating particularly the means for elevating the heel of the person whose foot is being measured;

Fig. 5 is a broken perspective view of the rear portion of one of the platforms depicting the means for removably securing the heel retainer to the platform when the device is prepared for use.

Referring to the drawing in detail, the numerals of which indicate similar parts throughout the several views, 7 designates generally each of a pair of box-like rectangular platforms which may be composed of cardboard or the like. The platforms 7 are hinged together along upper longitudinal edges by means of a strip of tape 8 or by any conventional means well known in the art, whereby one platform 7 may be turned over upon the other and the hinge 8 will prevent their lateral displacement with respect to one another while in transit through the mails or otherwise, as well as prevent confusion in the minds of the customer as to their arrangement for use. One platform 7 is provided for each of the customer's feet so that both may be measured at the same time. As the platforms are identical the following detailed description of one thereof will be understood to be a description of either.

The box 9 comprising each platform 7 is formed of a flat bottom 10 (Fig. 4), upright sides 11 and end walls 12, and a top 13 supported at its edges by sides 11 and end walls 12 a distance from the bottom 10 substantially equal to or slightly greater than the depth of the heel of an average shoe. At one end of top 13 the outline of a heel of a foot is delineated as indicated at 14. The ends of the heel line 14 converge and extend toward the opposite end of top 13 to represent the instep of the foot as at 15. The top 13 is cut through as at 17 along the instep line to sever the middle portion of the top from the flanking edges 16 thereof. The cuts 17 demarking the instep diverge outwardly a short distance and then sharply inwardly as at 18 (Fig. 4) a distance substantially equal to the thickness of the box and then again diverge on straight lines as at 19 parallel, respectively, to the lines of their diversion rearwardly of the inward cuts 18. The portions 20 of the top adjoining the last-named diverging straight cuts are folded downwardly on lines continuing the first diverging cuts of the instep so as to contact the bottom of the box and thereby afford support for the adjacent side edges 16 of the top and provide a backing for inserted width-blocks, hereinafter referred to more in detail.

Top 13 is cut inwardly as at 21 from the points of extreme diversion of cuts 19 distances slightly greater than the width of sides 11 and thence on lines parallel to the sides of the box to points adjacent, but equi-distantly spaced from, the end of top 13 opposite to that on which the heel is delineated as is indicated by the numeral 22. The portions 23 of top 13 adjacent each of the parallel cuts 22 are folded downwardly into contact with bottom 10 on lines parallel to but spaced from sides 11 of the platform slightly farther than the foremost points of the backing 20, so as to provide lateral support for the ends of a series of length-blocks, the size, shape and use of which is more fully described below.

Top 13 is further cut parallel to end walls 12 of the platform on a line 24 joining the forward

ends of cuts 22 so as to sever the forward end of the middle portion of the top therefrom and form a tongue 25.

Tongue 25 slopes downwardly from its point of joinder to the heel portion of the top, to the bottom of the box to simulate the portion of a shoe adapted to support the instep of a foot. The forward portion of tongue 25 is glued or otherwise secured to bottom 10. A tread piece 26 of stiff material overlies the tongue 25 and is attached thereto but is of an outline conforming in contour to the foot area of the platform.

A block of wood 27 or the like is interposed between top 13 and bottom 10 of the box at the rearward end of the latter to lend support to the heel portion which is elevated with respect to the ball and toe portion of the tongue 25 and tread piece 26.

A gauge block 28 is similarly secured in a stationary position under the lip 29 comprising the front end of the top between the parallel cuts 22.

A heel gauge or guard 29', shaped to conform generally to the heel of a person's foot and having a flanged base 30, is adapted for releasable attachment to the top in a position coinciding with the line 14 delineating the back of the heel. To this end a series of depending studs 31 are secured to flange 30 for reception in holes formed in top 13 and the supporting block 27 to retain the heel guard in the desired position but permit its removal when not in use.

In accordance with the use of my invention the platforms 7 are arranged as shown in Figs. 2 and 3. The heel guards 29' are placed in upright position at the back of the outline of the heel marked on the top of each platform where they may be retained by the engagement of studs 31 in the holes of the top. The customer then stands, without shoes, on the platform, arranging his feet with his heels firmly against guards 29'. His heels will thus be elevated with respect to the balls of his feet by supporting block 27. The weight of the customer's body should be distributed equally upon both feet in a manner closely approximating the normal conditions to which his feet will be subjected when the customer stands in properly-fitted shoes, insofar as such conditions affect the shape of his feet. With the customer's feet thus positioned on the platforms 7 the width and length thereof, in terms of shoe sizes, may be ascertained by the use of measuring blocks. The blocks 32, utilized for measuring the foot-length, are of a length to fit snugly between the parallel supporting portions of the top and are of different thicknesses. A block 32, one-sixth of an inch thick representing one half of a shoe size, and four additional blocks 32 of a thickness equal to different multiples of one-sixth of an inch are provided, whereby different ones of blocks 32 may be combined to equal a total thickness of from one sixth to any multiple of one sixth of an inch up to four and one sixth inches representing twelve and one-half shoe sizes. The stationary gauge block 28 is spaced from the installed heel guard 29', a distance sufficient to accommodate therebetween a foot taking the largest size shoe which the merchant can furnish, e. g. of the order of shoe size 14, as in the embodiment illustrated. With this spacing of the heel guard 29' and gauge block 28 and with blocks 32 of the thicknesses above indicated, any size foot taking from a one and one half size to a size fourteen shoe may be measured for a fitting by selecting the proper combination of the blocks 32 of suitable thickness, required to fill the area be-

tween the toes of the customer's foot and gauge block 28. Each block 32 may be stamped with the shoe size number which it represents when in use. The size of shoe required to fit a particular foot may be obtained by adding up the sizes stamped on the blocks 32 which are interposed between the toes of the customer's foot and the gauge block 28 and then deducting the total from the maximum size number i. e. 14, which may be gauged on the platform. To aid the customer in ascertaining the size shoe required to fit the particular foot measured the tread piece 26 may be calibrated to represent half and full sizes from the gauge block 28 towards the heel down to one and one-half size graduation. Even with the tread piece 26 so calibrated, blocks 32 are highly valuable in facilitating reading of the scale by the customer, as will be obvious to those of skill in this art.

The width of the shoes required to fit the customer's feet is ascertained with the aid of a series of thin strips 33, each one-twelfth of an inch in thickness and of a width substantially equal to the depth of box 9. The width strips 33 are inserted in pairs, one on each side of the foot against the backing 19. Backing portions 19 of the top are spaced apart a distance to represent the width of the widest shoe which the seller can furnish, e. g., a shoe having a width designated in the art as "E." Each pair of strips 33 interposed at the sides of the feet indicate a reduction in width of one size. A sufficient number of strips 33 may be included with the apparatus to narrow the area between the backing portions 19 to represent a shoe width of the order of "A" or "AA," as desired, in accordance with the conventional manner of designating width sizes.

As heretofore indicated the apparatus of my invention is intended for use by the customer who finds it inconvenient to attend the shoe store in person. Being hinged together, the platforms 7 may be easily prepared for mailing to the customer. The depression formed in each platform for the ball and toe of the foot of the customer may be large enough to accommodate all of the blocks 32 and strips 33, as well as heel guard 29' which is to be assembled with that platform. One platform may then be turned over upon the other to enclose the blocks 32, strips 33 and guards 29' and provide a compact package adaptable for facile wrapping and sealing in a well known manner.

It will be thus seen that the device of my invention is economical in manufacture and extremely simple to use yet affords support for the feet similar to that provided by a properly fitted shoe while carrying the weight of the body of the customer, so as to permit measurement of the feet while in the shape and form they will assume in shoes of proper fit.

While I have illustrated and described but one embodiment of my invention it will be appreciated that many changes may be made in size, design, number and proportion of the various parts, e. g., in the relative size of blocks 32 and strips 33, the elevation of the heel portion of the platform with respect to the support for the ball of the foot, or the contour of the heel guard, and that other well known means for securing the heel guards 29' in position may be substituted for that shown, without departing from the spirit of my invention as defined by the appended claims.

What I claim and desire to secure by Letters Patent is:

1. In a device of the character described, a

platform having a recess therein to receive a foot, means to delineate a position of the heel of the foot on said platform, and a series of blocks for interposition between the forward end of said recess and the toes of the foot for indicating, by the size and number of the blocks required to fill said area, the length of the foot.

2. In a device of the character described, a platform to receive a foot, having an abutment in advance of the toes of the foot to be measured, means to delineate a position of the heel of the foot with respect to said abutment, and a plurality of measure-indicating spacing members adapted for positioning between said abutment and the toes of the foot to indicate the length of the foot.

3. In a device of the character described, a platform to receive a foot, said platform having an elevated heel support and an abutment in advance of the toes of the foot to be measured, means to delineate a position of the heel of the foot on said heel support, and a plurality of measure-indicating spacing members for filling the area between the toes of the foot so positioned and said abutment for indicating by the size of said composite means the length of the foot.

4. In a device of the character described, a platform for the support of a foot to be measured, said platform having an abutment in advance of the toes of the foot, and abutments on each side of the foot, means to delineate a position of the heel of the foot with respect to said abutment, a plurality of measure-indicating spacing members for positioning between said abutment, and the toes of the foot to indicate the length of the foot, and a plurality of measure-indicating spacing members adapted to be placed between the foot and said abutment spaced from each side of the foot to indicate the width of the foot.

5. In a device of the character described, a platform having a depression therein for the support of a foot, portions of said platform forming oblique sides of said depression, an abutment at the forward end of said depression, means to delineate a position of the heel of the foot on said platform, said side portions being spaced apart a predetermined distance, said abutment and said last-named means being spaced apart a predetermined distance, and a series of blocks of predetermined thickness adapted for interposition between the foot and said side portions and between the toes of the foot and said abutment to indicate respectively by the number and size of said blocks the width and length of the foot.

6. In a device of the character described, a pair of platforms, each having a depression therein for the support of a foot, said depressions each having an abutment at their sides and at their respective forward ends means to hinge said platforms together for registry of said depressions with one another when the platforms are folded together, and means adapted for interposition between the feet and said abutments at sides and ends of said platforms respectively for gauging the width and length of the foot.

7. In a foot measuring device for shoe fitting, a base, a shallow foot-receiving receptacle having a floor formed in said base, the floor of said receptacle being flat, said receptacle having walls perpendicular to its floor, said walls roughly outlining a floor area larger than the sole and toes of the fore part of a foot to be measured, the front end wall of said receptacle and part of both side walls thereof enclosing three sides of a rec-

tangular floor area of said receptacle, the remaining portions of each of said side walls of said receptacle diverging from a heel rest and at an angle to said parallel side walls; a plurality of indicatively measured spacing members adapted to occupy said rectangular area of said receptacle, a plurality of strips of variable measured thicknesses adapted to occupy spaces between the sides of a foot to be measured and the angularly disposed portions of the side walls of said receptacle, a heel rest substantially level with the surface of said base, said heel rest being joined by an inclined plane surface to the floor of said receptacle, and a heel guard for said heel rest, substantially as and for the purpose described.

8. In a foot measuring device for shoe fitting, a platform, a shallow receptacle sunk below the surface of said platform, said receptacle being of larger lateral and longitudinal dimensions than the surface area of the sole and toes of the fore part of a foot to be measured, said receptacle having a floor and a front end wall and side walls, said last-mentioned walls being each perpendicu-

lar to the surface of said floor, a rear wall of said receptacle upwardly inclined to the surface of said platform, a heel rest, a heel guard, and a plurality of variably measured spacers to fill the space between the side walls and the front end wall of said receptacle and corresponding parts of a foot being measured, substantially as described.

9. As an article of manufacture, a duplex shoe fitting receptacle for coincidentally receiving for measuring fore parts of a right and left foot, said receptacle having floor areas adapted to support the fore part of the sole and toes of each foot, said areas being respectively surrounded by perpendicular walls, and also being of larger lateral and longitudinal dimensions than corresponding parts of the feet to be measured, said walls forming straight and vertical abutments at the sides and front ends of said receptacles, and a plurality of measure-indicating spacing members adapted to be inserted between end walls and side walls and each of the feet being measured.

ELMER JARED BLISS.
